UNITED STATES PATENT OFFICE.

FRANS JUSTINUS NILSSON, OF HUSQVARNA, SWEDEN.

MOLDING-MACHINE.

1,118,672.

Specification of Letters Patent. Patented Nov. 24, 1914.

Application filed May 22, 1911. Serial No. 628,687.

To all whom it may concern:

Be it known that I, FRANS JUSTINUS NILSSON, a subject of the King of Sweden, residing at Husqvarna, Sweden, have invented 5 certain new and useful Improvements in Molding-Machines, of which the following is a specification, reference being had to the drawings accompanying and forming a part hereof.

10 This invention relates to the molding of radiators for steam or hot water, low-pressure sectional boilers and other similar apparatuses, and the invention consists of a molding device which will be fully described hereinafter and finally pointed out in the claims.

In the accompanying drawings, Figure 1 shows a pattern-arrangement for two or more sections with the flask put on, filled 20 and ready for pressing, Fig. 2 shows a vertical section of the same arrangement with the pressed flask, and Fig. 3 is a horizontal section on the line A, A in Fig. 2.

Similar reference characters indicate corresponding parts throughout the different figures of the drawings.

When several sections are to be cast together in one piece, a longitudinally-slidable hollow plunger 1 (Figs. 1 and 2) is pressed 30 upward by means of a spring 2 and is pushed downward by the pattern 3 when the mold is pressed while the pattern comes directly in contact with the upper face of the plunger. The highest position of the plunger is defined by a collar 4 screwed in its lower end, the upper end of which collar abuts against the lower face of an outwardly-directed flange 6 on a tubular casing 5, that extends into the plunger and that is 40 fastened with its lower end to a bracket 8 fixed to the pattern-plate 7. The upper face of the casing 5 forms a bottom-support for the spring 2. The plunger 1 is guided partly by the pattern-plate 7 and partly by the 45 casing 5 upon which the collar slides, it being at its lower end provided with an outwardly-extending circumferential flange 9, the object of which is to prevent the plunger from raising itself when in its lowest position.

Fig. 3 shows a hook 11 with a handle 10. This hook is pivoted on a vertical pin 12 in the pattern-plate, and it is acted upon by a spring 13 that presses it against the plunger, in order that this latter may be

locked when in its lower position the flange 9 comes under the edge of the hook 11. The plunger can be loosened again by pulling the hook outwardly by means of the handle 10.

When the plunger 1 is in its lowest position (Fig. 2), the upper end 14 reaching above the pattern forms a pattern for the connecting part of the radiator-section. This corresponds to the lower part 15 of 65 the upper pattern-plate which in pressing the mold must bear upon and correspond with the upper clean face of the plunger, in order that the mold may be placed at the correct and proper pitch, *i. e.*, that the 70 proper distance between the center-lines of the sections may be obtained.

In the upper end of the plunger a bushing 16 of tempered steel is fastened on the same level with the top-face of the plunger 75 and provided with a downward extension forming a fastening for a sleeve 17, which serves for the purpose of protecting the interior of the plunger and the spring 2 against the ingress of sand and dust. The 80 bushing 16 has a central hole into which enters a corresponding plug 18 projecting from the upper pattern, whereby the contraction of the patterns and the connecting parts is facilitated. The plug as well as 85 the bushing is made of tempered steel and so arranged that they easily can be replaced when worn out.

The molding may be done in a double-press molding machine, *i. e.*, a molding machine with one-half of the pattern placed upon the machine-table and the other half of it on a top-piece that can be adjusted into proper relative position with the former. In order to get the proper quantity of sand 90 into each mold-box or flask, so that the mold may attain the proper hardness, a sand-measure 44 (Fig. 1) of suitable height is used. This sand-measure also serves as a stop for the pressing movement. The upper pattern-plate is provided with a part that fits in the sand-measure with a very small play and has exactly the same height as the sand-measure. After the mold-box 95 has been filled with sand and leveled off 100 even, the pressing takes place until the upper pattern-plate strikes against the upper edge of the sand-measure, whereby the upper pattern, being all the time in full contact, presses against the face of the plunger. 110

The plunger is locked in its lowest position after the pressing, so that it may not interfere with the lifting off of the mold.

The details, for instance the stopping devices for the highest and lowest position of the plunger, may be varied in several ways and the invention may be put in practice without any principal variations for the casting of sectional boilers in one piece or of other apparatuses consisting of a number of equal parts connected with each other, and in general producing integrally-cast objects.

I claim:

1. A molding device, comprising a lower pattern-plate having the form of one face of one section of the body to be cast, an upper pattern-plate having the form of the opposite face of an adjoining section and having a downwardly-extending projection corresponding to a part of a connecting piece between the two sections, a mold-box between said pattern-plates, and an upwardly spring-actuated plunger in the lower pattern-plate in the path of said projection of the upper pattern-plate and having its upper end in position to engage therewith free of the sand in said mold-box, said plunger having its upper part so shaped as, when depressed by said projection and in engagement therewith, to form that part of the mold corresponding to the remainder of said connecting piece between the two sections.

2. A molding device, comprising a lower pattern-plate having the form of one face of one section of the body to be cast, an upper pattern-plate having the form of the opposite face of an adjoining section and having a downwardly-extending projection corresponding to a part of a connecting piece between the two sections, a mold-box between said pattern-plates, an upwardly spring-actuated plunger in the lower pattern-plate in the path of said projection of the upper pattern-plate and having its upper end in position to engage therewith free of the sand in said mold-box, said plunger having its upper part so shaped as, when depressed by said projection and in engagement therewith, to form that part of the mold corresponding to the remainder of said connecting piece between the two sections, a removable downwardly-tapering centering plug in said projection, and a removable

bushing in said plunger adapted to receive said plug.

55

3. A molding device, comprising a lower pattern-plate having the form of one face of one section of the body to be cast, an upper pattern-plate having the form of the opposite face of an adjoining section and having a downwardly-extending projection corresponding to a part of a connecting piece between the two sections, a mold-box between said pattern-plates, an upwardly spring-actuated plunger in the lower pattern-plate in the path of said projection of the upper pattern-plate and having its upper end in position to engage therewith free of the sand in said mold-box, said plunger having its upper part so shaped as, when depressed by said projection and in engagement therewith, to form that part of the mold corresponding to the remainder of said connecting piece between the two sections, and means for retaining the plunger in depressed position after withdrawal of the upper pattern-plate.

70

4. A molding device, comprising a lower pattern-plate having the form of one face of one section of the body to be cast, an upper pattern-plate having the form of the opposite face of an adjoining section and having a downwardly-extending projection corresponding to a part of a connecting piece between the two sections, a mold-box between said pattern-plates, an upwardly spring-actuated plunger in the lower pattern-plate in the path of said projection of the upper pattern-plate and having its upper end in position to engage therewith free of the sand in said mold-box, said plunger having its upper part so shaped as, when depressed by said projection and in engagement therewith, to form that part of the mold corresponding to the remainder of said connecting piece between the two sections, and adjustable means for limiting the upward rise of the plunger.

95

In testimony that I claim the foregoing as my invention, I have signed my name in presence of two subscribing witnesses.

FRANS JUSTINUS NILSSON.
